SHAKER FOR FLOUR BREADING RECOVERY

John E. Friedrichs, Jr., 922 Wycliffe,
Houston, Tex. 77024

Filed Feb. 29, 1968, Ser. No. 10,793

Term of patent 14 years

Int. Cl. D15—05

U.S. Cl. D55—1

FIG. 2

FIG. 3

FIG. 1 is an isometric view of the top, front and the right side of a shaker for flour breading recovery showing my new design;

FIG. 2 is an isometric view of the bottom, rear and left side thereof;

FIG. 3 is a fragmentary isometric view of the top, rear and left side upper portion thereof, showing hopper, actuator and rear chute details; and

FIG. 4 is a plan view showing hopper design.

I claim:

The ornamental design for a shaker for flour breading recovery, as shown and described.
